UNITED STATES PATENT OFFICE.

HENRY J. COBEN, OF CLEVELAND, OHIO.

DESIGN FOR A SINK-BOARD.

SPECIFICATION forming part of Design No. 20,922, dated July 7, 1891.

Application filed May 25, 1891. Serial No. 394,062. Term of patent 14 years.

To all whom it may concern:

Be it known that I, HENRY J. COBEN, a citizen of the United States, residing at Cleveland, in the county of Cuyahoga and State of Ohio, have invented and produced a new and original Design in Drip-Boards for Sinks, of which the following is a specification, reference being had to the accompanying drawings, in which—

- 10 Figure 1 is a perspective view of a drip-board, showing my design. Fig. 2 is a longitudinal section thereof on the line of one of the grooves and showing the gradually-increasing depth of the groove.
- 15 A represents the board in its entirety, and *a* the surface of the border along the sides and at the upper end of the board. The intervening space *a'* between the borders at the side consists in a surface that is formed in

regularly-scalloped lines transversely running from the plane of the surface of the borders down and up at regular intervals and of varying degree in depth from the upper to the lower end of the board. This scalloped surface has only a very slight portion *c* along 20 the top center of each rib *d* on a plane with the surface of the side borders *a*, and the remainder of said surface runs on lines substantially as shown and on a lower plane.

Having thus described my design, what I 25 claim is—

The design for a sink-board, substantially as herein shown and described.

HENRY J. COBEN.
